UNITED STATES PATENT OFFICE.

ADAM DIEHL, OF SPRINGFIELD, OHIO.

MOLDING-MACHINE.

1,342,428.

Specification of Letters Patent.

Patented June 8, 1920.

Application filed February 2, 1920. Serial No. 355,545.

To all whom it may concern:

Be it known that I, ADAM DIEHL, a citizen of the United States, and a resident of Springfield, in the county of Clark and State of Ohio, have invented certain new and useful Improvements in Molding-Machines, of which the following is a specification.

My invention is an improvement in molding machines, and the invention has for its object to provide simple mechanism for use in connection with such machines for simultaneously lifting the cope and the match plate from the drag, wherein the lifting mechanism is operated by a single lever under the control of the operator, and wherein the parts are held parallel during the separation.

In the drawings:

20 Figure 1 is a side view of a molding machine provided with the improved mechanism;

Fig. 2 is a plan view showing the connection of the cope with the lifting mechanism;

25 Fig. 3 is a partial vertical section showing the arrangement of the cam shaft and its connection with the cope and drag;

Fig. 4 is a section taken substantially on the line 4—4 of Fig. 3.

30 The present embodiment of the invention is shown in connection with a mold, consisting of the usual drag 1, cope 3 and match plate 2. At each end of the match plate there is journaled a shaft 4, each shaft being journaled in brackets 4^a on the match plate, and each of these shafts carries at each end an S-shaped cam 5, the said cams having at their centers hubs which are secured on the shafts.

40 Each cam is arranged in a housing 6 of substantially cylindrical form, having radially vertically extending nipples 7 through which are slid able plungers 8, and each plunger is provided at its inner end with a roller 9 for engaging the adjacent cam 5.

Angle plates 10 and 11, respectively, are secured to the corners of the cope and drag, by means of screws 12 or the like, each plate having one portion abutting the outer face of the cope or drag and another portion extending laterally outward therefrom. The outwardly extending portion of each angle plate 10 is above the outer end of the uppermost plungers 8, and the outwardly extending portions of the angle plates of the drag extend below the lowermost plungers 8. A

set screw 13 is threaded through each of the outwardly extending portions of the angle plates 10 and 11, into engagement with the end of the adjacent plunger, and a lock nut 14 is provided on each set screw for holding the set screw in adjusted position.

It will be obvious from the description that when the shafts 4 are oscillated, by mechanism to be presently described, the cams which are similarly arranged on the shafts, will be operated to simultaneously move the plungers 8 away from the shaft or toward the shaft. Since the lowermost plungers 8 cannot move downwardly because the drag is fixed, the cams and the cam shafts will be moved upwardly, lifting the match plate 3 from the drag and simultaneously lifting the cope 2 from the match plate.

A lever 15 is provided for simultaneously operating all of the cams. This lever is pivoted at 16 to a bracket 17 on the match plate 2, and links 18 connect this lever above and below its pivotal connection with radial arms 19 on the shafts 4. Referring to Fig. 80 1, it will be seen that each link 18 has a series of openings for engagement by the pin 19^a, which pivotally connects the link and the lever. Thus the aggregate distance between the levers and the radial arms may be 85 adjusted to vary the extent of movement of the cope and match plate with respect to the drag. The housings 6 are sectional, as shown, the sections having radial lugs 20 which are engaged by bolts and nuts 21, and these housings, in practice, will be filled with a lubricant of any desired character.

In operation, when it is desired to separate the parts of the flask, the lever 15 is swung in a direction to simultaneously move 95 all of the cams in a similar manner, that is, in a manner such that all of the plungers will be simultaneously moved away from the shafts 4, and the cams are so connected to the lever that they will be so moved. When, 100 for instance, the grip end of the lever 15 is swung away from the left of Fig. 1 and toward the right the cams will be oscillated to move the plungers outwardly, and the cope and match plate will be separated from the 105 drag and from each other, and they will be moved apart on parallel lines.

The improvement is an interchangeable device, which can be removed from one match plate and attached to another or 110 others. The device is so constructed that it can be attached to match plates varying in

thickness from one-eighth of an inch to one inch or more, with only the need of adjusting the set screw 13 on the angle iron 11 of the drag 1.

5 I claim:

1. In molding machines, the combination with the flask, of means for simultaneously separating the cope and the match plate from the drag and from each other while retaining the parts in parallel relation, said means comprising shafts journaled at the ends of the match plate and supported by the match plate, cams secured to the ends of the shaft, plungers arranged above and below the cams and moved by the cams, adjustable stops on the cope and drag for engagement by the plungers, means for simultaneously moving the shafts to cause the cams to move in a direction to simultaneously move all of the plungers from the shafts, said means comprising a lever pivoted to the match plate, radial arms on the shafts, and links connecting said arms with the lever above and below the shaft.
- 15 2. In molding machines, the combination with the flask, of means for simultaneously separating the cope and the match plate from the drag and from each other, while retaining the parts in parallel relation, said means being carried by the match plate.
- 20 3. In molding machines, the combination with the flask, of means for simultaneously separating the cope and the match plate from the drag and from each other, while retaining the parts in parallel relation, said means being carried by the match plate.
- 25 4. In molding machines, the combination with the flask, of means for simultaneously separating the cope and the match plate from the drag and from each other, said means being carried by the match plate.

separating the cope and the match plate from the drag and from each other while retaining the parts in parallel relation, said means comprising shafts journaled at the 30 ends of the match plate and supported by the match plate, cams secured to the ends of the shaft, plungers arranged above and below the cams and moved by the cams, adjustable stops on the cope and drag for engagement 35 by the plungers, and means for simultaneously moving the shafts to cause the cams to move in a direction to simultaneously move all of the plungers away from the shafts.

3. In molding machines, the combination 40 with the flask, of means for simultaneously separating the cope and the match plate from the drag and from each other, while retaining the parts in parallel relation, said means being carried by the match plate.

4. In molding machines, the combination with the flask, of means for simultaneously separating the cope and the match plate from the drag and from each other, said means being carried by the match plate.

ADAM DIEHL
